UNITED STATES PATENT OFFICE.

GURDON T. POLLARD, OF DENVER, COLORADO.

AUTOMATIC WORK AND FEED DEVICE.

Application filed September 5, 1924. Serial No. 736,187.

The invention relates to improvements in automatic work and feed devices and, although adapted to many applications, it is more particularly adapted to be used in connection with rotary well drilling machinery and equipment.

The principal object of the invention is to provide an efficient means for controlling the load on a work device, such as, a cutter or 10 drill, whereby the said work device is actuated and fed to its work in such manner as to be subjected to a substantially constant, predetermined load or resistance regardless of varying conditions of work encountered.

Another object of the invention is to provide means for automatically varying the operating speed of the work device and its rate of feed in accordance with the resistance encountered by said work device in accomplishing its work, said means being capable of withdrawing said work device from the work when the resistance has reached a maximum value and returning same when the resistance reaches a predetermined value.

Still another object is to provide means whereby a differential or reversing effect can be obtained in the usual draw works of a rotary well drill outfit and in the hoisting mechanism usually employed, whereby the tool 30 may be fed or withdrawn under a fine control.

A still further object is to provide a mechanism for accomplishing the above results which may be attached to, and used in connection with, the present type of rotary drilling equipment.

Other objects and advantages reside in the detail construction of the invention, which result in simplicity, efficiency, and economy, 40 and which will become more apparent from the following description.

In the following detailed description of the invention, reference is had to the accompanying drawings which form a part hereof. 45 Like numerals refer to like parts in all views of the drawings and throughout the description.

In the drawings:

Fig. 1 is a plan view of one form of the improved automatically operating work and feed device, as applied to a rotary well drilling outfit. In this view the differential gear sets are shown in section.

Fig. 2 is a detail cross section through the

differential gear sets and is taken on the line 55 2-2, Fig. 1.

Fig. 3 is a similar cross section through, what will be hereinafter termed, the "change gears". This view is taken on the line 3-3, Fig. 1.

Fig. 4 is a vertical section taken on the line 4-4, Fig. 1. In this view the derrick hoisting mechanism is illustrated.

Fig. 5 is an end elevation of an alternate form of the invention. This form is similar to the form of Figs. 1 and 4, with the exception that the differential gear sets, illustrated in Fig. 2, have been eliminated.

Fig. 6 is a diagrammatic view illustrating the principles involved in the apparatus of Fig. 5.

Let the numeral 10 designate the usual "grief stem" of the drilling mechanism, which is squared near its upper extremity, for engagement in a rotary table 11, and terminates at the bottom of the well in a drill bit 12. The table 11 carries bevel gear teeth which are engaged by a bevel pinion 13, through the medium of which, the table 11, drill stem 10, and bit 12, are revolved. The 75 pinion 13 is carried on the extremity of a drive shaft 14, which is operatively connected to a countershaft 15, through the medium of a pair of miter gears 16 and 17. A braking mechanism 18 is carried by the drive shaft 14, by means of which speed of revolution of the drill bit 12 may be controlled.

Owing to the excessive weight of the drill stem 10, in a deep well, it would be impractical to allow the bit 12 to support the entire weight. To relieve this weight on the bit 12, the drill stem 10 is supported through the medium of a cable 19 which passes from a hoist drum 20, upward to the crown block frame 21 of the derrick, where it is trained over multiple sheave wheels 22 and a multiple block 23, secured to the upper extremity of the drill stem 10; thence over a sheave 24, terminating in a swivel joint 25 carried by a vertically-operable feed screw 26, the operation of which will be later described.

The hoist drum 20 is carried on a drum shaft 27, upon which it is free to revolve, but to which it may be locked by a clutch 28. Two brake bands 29 are provided for the 105 drum 20 through which its movement may be controlled.

Affixed to one extremity of the shaft 27, is

a bevel gear 30 which meshes with teeth carried by a nut 31 which is in turn threaded onto the feed screw 26. Affixed to the other extremity of the drum shaft 27 is a disk 32, 5 which carries a series of planet gears 33.

Acting as an extension of the drum shaft, but separate therefrom, is a short shaft 34, which will be hereinafter designated the second differential shaft. Affixed to the second 10 differential shaft 34 is a sun pinion 35, which meshes with the planet gears 33 of the shaft 27, and a spur gear 36.

Acting as an extension of the counter shaft 15, but separate therefrom, is a short shaft 37, 15 which will be hereinafter designated the first differential shaft. Affixed to the first differential shaft 37, is a spur gear 38 and a disk 39 which carries a series of planet gears 40 arranged to mesh with a sun gear 41 secured 20 to the extremity of the countershaft 15.

An idler gear 42 is placed between, and in mesh with both, the spur gears 36 and 38. The gears 36, 38, and 42 are removable and interchangeable so that various gear ratios 25 may be obtained between the differential shafts 34 and 37. They are therefore designated the change gears.

Power for driving the entire mechanism is derived from a power shaft 43 which may be 30 connected through the medium of a sprocket 44 with any suitable source of power. For the device as disclosed, however, the power shaft 43 will be considered the source of power.

35 The power shaft 43 carries a spur gear 45, which meshes with a ring gear 46, rotatably mounted on the countershaft 15. The ring gear 46 meshes with a relatively larger though similar ring gear 47 which is rotatably mounted on the second differential shaft 34.

The ring gears 46 and 47 are free to revolve on their respective shafts and each carry interior gear teeth, those of the gear 46 meshing 45 with the series of planet gears 40 and those of the gear 47 meshing with the series of planet gears 33.

In operation, the drill stem 10 is lowered by allowing the drum 20 to rotate free from 50 its shaft, until the bit 12 has bottomed in the well. The brake 29 is now locked to prevent rotation of the drum 20. Power is supplied from the power shaft 43 and travels through the first differential gear set, comprising gears 46, 40 and 41, to the countershaft 15, thence to the drive shaft 14 and to the drill bit 12. Power will also flow through the 55 differential gear set, comprising gears 33, 35, and 47, to the drum shaft 27 and will, through the medium of the bevel gear 30, rotate the nut 31 and allow the feed screw to travel and feed the bit 12 to its work, through the medium of the cable 19. The normal direction 60 of rotation of the gears is indicated in Figs.

2 and 3. The sun gear 35 and ring gear 47 rotate in opposite directions at substantially the same speed, thus holding the planet gears stationary in their orbits so that there will be no feeding of the feed screws 26.

Should the resistance to rotation of the bit 12 be sufficiently excessive, however, the sun gear 41 will be stopped. This will immediately cause the planet gears 40 to rotate on their individual axis and decrease their orbital speed, thus decreasing the speed of the shafts 37, and 34, and the second sun gear 35, causing its speed to become less than that of the ring gear 47 and allowing the planet gears to follow the ring gear (clockwise in Fig. 2), 80 and rotate the shaft 27 so as to cause the nut 31 to draw in the feed screw 26 until the load on the bit has been lessened to predetermined degree, when the sun gear will begin to revolve and the drill will resume its normal operation.

Should the resistance on the bit diminish, the sun gear 41 will increase its speed. This increase will be immediately communicated, as above described, to the sun gear 35 which 90 will increase its speed over that of the ring gear 47 and, since the sun and ring gear are traveling in opposite directions, will cause the planet gears 33 to follow the sun gear 35 (anti-clockwise Fig. 2) and rotate the nut 31 95 so as to let out the feed screw 26 and allow the drill to lower in the well. When the resistance has again built up to normal the normal operation will be resumed.

It will be seen from the above that variations in the operating speed are entirely automatic and that these automatic variations immediately and automatically cause the feed mechanism to adjust the feed to suit conditions.

The feed screw 26 may be splined, as shown at 48, to prevent its rotation and dead ends 49 and 50 are provided so that the shaft 27 may be used to operate the drum 20, for setting casing etc., without operating the feed 110 screw 26.

In the alternate form, shown in Figs. 5 and 6, the differential gears are eliminated and the nut and screw regulation is affixed to the drum shaft 27 of the usual draw works, the 115 countershaft 15 having the usual connections, by clutch, to the drum shaft 27. This form is not automatic but is designed to be used in connection with the present draw works to assist the operator in minutely adjusting the feed or withdrawal of the drill bit 12, the cable 19 being so connected as to obtain a differential action therein without the use of gears. In this form, the cable connections are identical with the form previously described.

The feed screw 26 is arranged so that it may be moved upward or downward at any speed by controlling the rotation of drum shaft 27. The drum may be rotated in either direction by the manipulation of the clutch 28 or the 130

brake 29. Thus, the portion of the cable 19 from the feed screw, indicated at 51 Fig. 6, may be given a plus, minus, or zero movement and that portion of the cable from the drum, 5 indicated at 52 Fig. 6, may also be given a plus, minus, or zero movement, as indicated in the same figure. The resultant of the two above movements will be communicated to the drill stem 10. The movement here will 10 be an addition or a subtraction of the movements at 51 and 52 or a differential movement.

In use, the shaft 27 could be allowed to constantly rotate the feed screw 26 so as to draw 15 inward (minus direction) on the portion 51 of the cable. The drum brake 29 could then be slowly released to feed the bit 12 to the work. It is difficult in present practise to release the brake carefully enough so as not to 20 overfeed, since the feed must be very slow, usually a release of one-half inch per time being sufficient. With the arrangement above described, however, the operator is allowed greater latitude, since the inpull of the screw 25 will be subtracted from his release and should be accidentally over feed or "bottom" his drill, the screw 26 will immediately act to again raise it.

While I have herein illustrated and described in some detail, forms of my invention, it is understood that the invention is not to be regarded as limited to the precise constructions described, except in so far as such limitations are included within the terms of the 35 accompanying claims, in which, it is my intention to claim all novelty inherent in my invention as broadly as is permissible in view of the prior art.

Having thus described my invention, what 40 I claim and desire secured by Letters Patent is:—

1. The combination of a rotatable and a vertically movable drilling member with differential rotating means and flexible hanging 45 means controlled to feed a drilling member to its work; said hanging means comprising a rope tackle with one end of the rope attached to a threaded rod; a hoisting drum attached to the other end of the rope and a nut arranged to travel on the said rod, and means for varying the rate of travel of the said 50 nut and the unwinding of the said drum in accordance with the resistance encountered while drilling; thereby causing a differential 55 action in the flexible hanging feeding means.

2. In a rotary drilling mechanism, a rotatable and vertically movable drill stem; means for rotating said drill stem; flexible means for supporting and vertically adjust-

ing said stem; a threaded rod secured to the 60 extremity of said flexible means; a nut arranged to travel on and move said rod longitudinally and means for rotating said nut relatively to the speed of rotation of said 65 drill stem and the resistance encountered in said rotation.

3. In a rotary drilling mechanism comprising a prime mover, a differential gear set arranged to rotate the said drilling mechanism, a differential gear set arranged to operate in conjunction with the said drilling mechanism and so arranged to feed a flexible hanging feeding means; said feeding means consisting of a threaded rod operated in a nut which is turned by the prime mover; and connected to the said threaded rod is one end of a rope tackle; while the other end of the said rope tackle is attached to a drum which is also operated by the said prime mover; the resulting action imparting a pull, or a 80 let out, to the ends of the said rope tackle and connected to drilling stems, thereby feeding the drilling tool to its work.

4. In a rotary drilling mechanism, means for rotating and means for feeding the drill 85 to engagement, arranged in conjunction with a double differential gear set, with a rope tackle, a hoisting drum, a threaded rod and nut attached to one end of said rope tackle and the other end of the rope wound around 90 the said drum, and so operated as to produce a differential action in the said feeding means.

5. Means for rotating and feeding the drill in a rotary drilling mechanism comprising a 95 prime mover; a planetary gear set arranged to be driven by said prime mover; said set adapted to rotate said drill; a second planetary gear set driven from said first set; cable means for supporting said drill; a threaded 100 rod secured to one extremity of said cable means; a nut operating to move said rod longitudinally; a reel secured to the other extremity of said cable means, said nut and said reel being arranged to be operated from 105 said second set of planetary gears.

6. The combination of a rotatable, vertically movable drilling tool, flexible means for supporting said tool at some intermediate point in said flexible means; a longitudinally 110 movable feed screw secured to one extremity of said flexible means and a winding drum secured to the other extremity thereof and means for rendering said mechanism operative, substantially as specified.

In testimony whereof, I affix my signature.

GURDON T. POLLARD.
